UNITED STATES PATENT OFFICE.

LEE J. BLACK, OF BEAUMONT, TEXAS.

ROTARY DRILLING APPARATUS.

1,144,098.

Specification of Letters Patent. Patented June 22, 1915.

Application filed July 30, 1914. Serial No. 854,059.

To all whom it may concern:

Be it known that I, LEE J. BLACK, a citizen of the United States, residing at Beaumont, in the county of Jefferson and State 5 of Texas, have invented certain new and useful Improvements in Rotary Drilling Apparatus, of which the following is a specification.

This invention relates to that class of 10 well drilling apparatus commonly known as rotaries, the same being characterized by a turntable carrying means for gripping the drilling pipe or tube.

The invention has reference more particularly 15 to the gripping device, and its object is to provide a simple and efficient device of this kind in which all screws and nuts of the ordinary gripping devices are eliminated and the number of parts is reduced to 20 a minimum, and also to provide a gripping device which can be easily and quickly operated.

Other objects and advantages of the invention will be pointed out in the detailed 25 description appearing hereinafter, reference being had to the accompanying drawings in which—

Figure 1 is a plan view of the gripping device, partly broken away; Figs. 2 and 3 30 are sections on the lines 2—2 and 3—3, respectively, of Fig. 1, the turntable not being shown in Fig. 3; Fig. 4 is an elevation of a locking device, and Fig. 5 is a cross-section on the line 5—5 of Fig. 1.

Referring specifically to the drawings, 35 10 denotes the turntable which carries the pipe-gripping device.

The turntable is mounted on sills 11 and 40 it is driven in the ordinary manner. As nothing is claimed for the turntable *per se* a further description thereof is deemed unnecessary.

The pipe-gripping device which is the 45 subject-matter of the present application for patent is constructed and arranged as follows:

In an annular recess 12 in the top of 50 the turntable 10 is mounted a circular housing comprising a bottom 13, a side wall 14 and a cover or top 15, the latter being removable to permit assemblage of the parts which the housing is to inclose. In the housing are mounted radially slidable jaws 16, each of which carries a roller 17 to engage the surface of the pipe or tube to be

rotated. The jaws are located diametrically opposite each other, and they are mounted to advance toward or to recede from a common center, the rollers being carried by the inner ends of the jaws. As 60 shown in Fig. 1, four jaws are provided. The periphery of the rollers is milled or otherwise shaped to obtain a firm hold on the pipe or tube to be rotated. The inner ends of the jaws are recessed, as indicated 65 at 18 to accommodate the rollers, and in the opposite side walls of these recesses are vertical grooves 19 in which seat the journals 20 of the rollers. The grooves open through the top of the jaws and the journals are slidable therein to permit the rollers to rise and fall, which eliminates the chatter or upward thrust away from the jaws. This is an important feature as there 70 is a constant vibration up and down when 75 drilling in rough or bouldered strata. The cover plate 15 has a central opening 21 to accommodate the pipe or tube to be rotated, and in the edge of this opening are slots 22 to accommodate the rollers, the latter being free to rise until their journals 80 come against the cover plate.

The jaws 16 are operated simultaneously 85 by means of a scroll plate 23 rotatably mounted in the housing. This scroll plate 90 is annular and in its inner edge are recesses 24 into which the outer ends of the jaws extend, there being a separate recess for each jaw. As shown in Fig. 1, the inner end wall of the recesses is spirally or eccentrically arranged and the outer ends of the jaws are correspondingly curved to fit snugly thereagainst. In the bottom of the scroll plate 95 are grooves 25 which run parallel to the spiral wall. The outer ends of the jaws 100 have upstanding ribs 26 which are curved to conform to the curvature of the grooves 25 and seat therein. The jaws slide on the bottom 13 of the housing and the scroll plate is spaced therefrom a sufficient distance 105 to allow the outer ends of the jaws to come beneath the scroll plate and the ribs 26 to seat in the grooves 25. The bottom of the housing also has a central opening 27 to accommodate the pipe or tube to be rotated, said opening being in line with the opening 21 of the cover plate 15. The recesses 24 of the scroll plate have overhanging top portions under which the outer ends 110 of the jaws are located and which prevents

the jaws from rising. The cover plate 15 fits on top of the scroll plate and prevents the latter from rising to take the ribs 26 out of the grooves 25.

5 In the housing are raised portions 28 between which the jaws 16 are mounted, the sides being machined to form guides for the jaws. The outer surface of these raised portions is curved to conform to the curvature of the inner periphery of the scroll plate, said plate fitting between said curved surface and the side wall 14 of the housing. These raised portions also carry the bolts 29 whereby the cover plate 15 is held 10 in place on the housing.

15 The scroll plate 23 is rotated by means of radial stems 30 secured to the outside thereof and passing through slots 30^a in the side wall 14 of the housing. When the scroll plate is rotated in one direction the jaws 16 are advanced to engage the gripping rollers 17 with the pipe or tube to be rotated, and upon turning the scroll plate in the opposite direction the jaws are retracted to release 20 the gripping rollers from the pipe or tube. The thrust on the jaws to advance the same is squarely against the outer ends thereof. The grooves 25 and the ribs 26 serve merely to retract the jaws and there is no strain on 25 these parts when the jaws are advanced.

30 A means is also provided for locking the jaws 16 in advanced position, the same comprising eccentric levers 31 fulcrumed between bearings 32 mounted on the outside of 35 the wall 14 of the housing. The eccentric ends of the levers work in openings 33 in the wall 14 so that they may be jammed against the outer periphery of the scroll plate 23, whereupon said plate is locked, 40 and prevented from turning in a direction to retract the jaws.

45 On the sills 11 is mounted a device for automatically operating the scroll plate 23. This device comprises a trip lever 34 having two arms or branches 35 and 36, respectively, and pivoted at 37 to a bracket 38 rising from the sills. An operating rod 39 is connected to the lever. To turn the scroll plate in a direction to retract the jaws, the 50 turntable 10 is driven in the reverse or left-handed direction, and the lever 34 is swung so that the arm 36 intercepts or comes in the path of the stems 30. Now, when one of the stems reaches the arm 36, the latter 55 being stationary, the scroll plate is rotated in a direction to retract the jaws and the operator may now pull out the pipe or tube should he so desire. On resuming drilling, the turntable is driven right-handed, and 60 the lever 34 is swung to place the branch 35 into the path of the stems 30, so that when one of the latter strikes the branch 35, the scroll plate is turned in a direction to advance the jaws, and to engage the rollers 17 65 with the pipe or tube. The dotted lines in

Fig. 5 show the lever 34 in the two positions to operate the scroll plate. When in normal position, as shown in full lines, the two branches of the lever are out of the path of the stems 30.

70 From the bottom 13 of the housing depend stems 40 which seat in recesses in the turntable 10, whereby the housing and the parts carried thereby are connected to the turntable to rotate therewith. Any other means 75 may be provided for connecting the housing to the turntable, and it may also be formed integral therewith. Various other changes in the structural details hereinbefore described may also be resorted to.

80 By the structure hereinbefore described a simple and highly efficient clamping device is had, and one which can be easily and quickly operated. All nuts and screws are eliminated and the structure is strong, 85 durable and simple, the number of parts being reduced to a minimum. The gripping rollers tightly grip the pipe or tube without danger of crushing the same. By recessing the top of the turntable and mounting the 90 device in the recess, the height of the apparatus is reduced which makes it more convenient for the operator in pulling out and putting in the pipe or tube.

95 I claim:

1. The combination of a rotary member, an annular scroll plate carried by the rotary member and rotatable therewith and relative to said member, said scroll plate having recesses, the inner ends of which are spiral, 100 radially movable jaws carried by the rotatable member and having their outer ends engaging the spiral inner ends of the scroll plate recesses, guides for the jaws, and means for rotating the scroll plate relative 105 to the rotary member for operating the jaws.

2. The combination of a rotary member, an annular scroll plate carried by the rotary member and rotatable therewith and relative to said member, said scroll plate having recesses, the inner ends of which are spiral, 110 and the bottom of the scroll plate having grooves which are parallel to the aforesaid spiral inner ends of the plate recesses, radially movable jaws carried by the rotatable member and having their outer ends abutting against said ends of the scroll plate recesses, and provided with ribs which seat in the aforesaid grooves, guides for the jaws, 115 and means for rotating the scroll plate relative to the rotary member for operating the jaws.

3. The combination of a rotary member, a circular housing carried by and rotatable with said member, said housing comprising a bottom, a side wall and a cover plate, the bottom and the cover plate having central openings, an annular scroll plate rotatably mounted in the housing radially movable 125 jaws operatively connected to the scroll 130 plate.

plate, guides in the housing for the jaws, and means for rotating the scroll plate relative to the rotary member for operating the jaws.

- 5 4. The combination of a rotary member, a circular housing carried by and rotatable with said member, said housing comprising a bottom, a side wall and a cover plate, the bottom and the cover plate having central 10 openings, an annular scroll plate rotatably mounted in the housing, radially movable jaws operatively connected to the scroll plate, guides in the housing for the jaws, the scroll plate being mounted between the 15 guides and the sidewall of the housing, and means for rotating the scroll plate relative to the rotary member for operating the jaws.

5. The combination of a rotary member, a circular housing carried by and rotatable 20 with said member, said housing comprising a bottom, a side wall and a cover plate, the bottom and the cover plate having central openings, an annular scroll plate rotatably mounted in the housing, radially movable 25 jaws operatively connected to the scroll plate, guides in the housing for the jaws, the scroll plate being mounted between the guides and the side wall of the housing, and said scroll plate having parts which over- 30 hang the jaws, and means for rotating the scroll plate relative to the rotary member for operating the jaws.

6. The combination of a rotary member, a scroll plate carried by the rotary member 35 and rotatable therewith and relative to said member, radially movable jaws operatively connected to the scroll plate, said jaws having recesses at their inner ends, the opposite side walls of the recesses having grooves 40 opening through the top of the jaws, gripping rollers seating in the recesses and having journals which seat loosely in the grooves, guides for the jaws, and means for

rotating the scroll plate relative to the rotary member for operating the jaws.

7. The combination of a rotary member, a housing carried by and rotatable with said member, a scroll plate rotatably mounted in the housing, radially movable jaws in the housing operatively connected to the scroll 50 plate, said jaws having recesses at their inner ends, the opposite side walls of the recesses having grooves opening through the top of the jaws, gripping rollers seating in the recesses and having journals which seat 55 loosely in the grooves, the top of the housing having slots which are in line with the gripping rollers, guides for the jaws, and means for rotating the scroll plate relative to the rotary member for operating the jaws. 60

8. The combination of a rotary member, a housing carried by and rotatable with said member, a scroll plate rotatably mounted in the housing, radially movable jaws in the housing operatively connected to the scroll 65 plate, and means carried by the housing and engageable with the scroll plate for locking the same against rotation in the housing, and guides for the jaws.

9. The combination of a rotary member, a scroll plate carried by the rotary member and rotatable therewith and relative to said member, radially movable jaws operatively connected to the scroll plate, guides for the jaws, actuating stems connected to the scroll 70 plate for rotating the same relative to the rotary member to operate the jaws, and a trip device adjustable to intercept said stems. 75

In testimony whereof I affix my signature 80 in presence of two witnesses.
